Primary Examiner — Rhea Shields

(57) **CLAIM**

The ornamental design for a charger, as shown and described.

DESCRIPTION

FIG. 1.1 is a perspective view of a charger, showing my new design;

FIG. 1.2 is a front elevation view thereof;

FIG. 1.3 is a side view thereof, taken from the right of FIG. 1.2, the opposite side view being a mirror image thereof;

FIG. 1.4 is a back view thereof; and

FIG. 1.5 is a top view thereof.

In the reproductions, the broken lines are for the purpose of illustrating environment only and form no part of the claimed design.
